DESCRIPTION

U.S. PATENT DOCUMENTS

D18,820 S * 12/1888 Stanley D12/111
D104,140 S * 4/1937 Henry D12/111
D151,110 S * 9/1948 Walker D12/111
D216,538 S * 2/1970 Hill D12/111

FIG. 1 is a perspective view of a frame for a high-performance balance bicycle.

FIG. 2 is a first side view thereof;

FIG. 3 is a second side view thereof;

FIG. 4 is a bottom view thereof;

FIG. 5 is a top view thereof;

FIG. 6 is a rear view thereof;

FIG. 7 is a front view thereof; and,

FIG. 8 is a perspective view thereof shown in an exemplary environment.

The broken lines are included for the purpose of illustrating
the environment structure and form no part of the claimed
design.
